UNITED STATES PATENT OFFICE.

HENRY V. WILLE, ROBERT M. CAMPBELL, AND WILLIAM J. ETHERINGTON, OF PHILADELPHIA, PENNSYLVANIA, ASSIGNEES TO THE BALDWIN LOCOMOTIVE WORKS, OF PHILADELPHIA, PENNSYLVANIA, A CORPORATION OF PENNSYLVANIA.

FRAME FOR ELECTRIC LOCOMOTIVES.

Application filed August 25, 1925. Serial No. 52,396.

The invention relates particularly to integral cast frames for small electric locomotives of the type commonly used in mines. The principal object of the invention is to provide a cast frame having various necessary parts of the locomotive structure cast integrally therewith, the formation of the frame being such as to provide maximum strength in proportion to the weight. Further objects will be apparent from the following specification and claims.

In the accompanying drawing there is shown the embodiment of the invention which is now deemed preferable, but it will be understood that various changes and substitutions may be made within the scope of the claims without departing from the spirit of the invention.

Of the drawing:

Fig. 1 is a plan view of a locomotive frame.

Fig. 2 is a side view.

Fig. 3 is a transverse sectional view taken along the line 3—3 of Fig. 2.

Figs. 4 and 5 are fragmentary plan and side views similar respectively to Figs. 1 and 2, but showing an alternate form of the invention.

Fig. 6 is a fragmentary sectional view taken along the line 6—6 of Fig. 2.

Fig. 7 is a fragmentary sectional view similar to Fig. 6 and showing an alternate form of the invention.

Referring to the drawing, 1 represents as an entirety the locomotive frame which is an integral steel casting. The frame comprises main side sections 2, 2 and end sections 3, 3.

Each of the side sections 2, 2 is provided with two recesses 4, 4 adapted respectively to receive the bearing boxes for axles 5, 5 which are connected with main supporting and driving wheels 6, 6. Each side section 2 includes two separated elements 7 and 8 which extend horizontally, the upper element 7 being supported by end uprights 9 and 10. Preferably and as illustrated, each lower element 8 is provided with two apertures at 11, 11 for supporting posts 12, 12, which at their lower ends engage the bearing boxes and which at their upper ends engage springs located between the said elements 7 and 8. Preferably an upright tie element 13 connects the two members 7 and

8 near the middle, thus providing two separate spring recesses. It is preferred to provide springs 14, 14 of the leaf type and when such springs are used supporting links are provided which engage lugs 15, 15 cast integrally on the side members. By referring particularly to Figs. 3 and 6, it will be noted that the elements 7 and 8 are both channel-shaped, the element 7 being inverted. The leaf springs 14, 14 are so positioned that if necessary they can extend into the upper channel sections 7.

In some cases it may be preferable to use coil springs 14^a, as shown in Fig. 7, instead of the leaf springs 14 as shown in the other figures. In this case a post 12^a is used and the upper end of the coil spring abuts directly against the upper frame element 7. The supporting lugs 15, 15 are omitted.

In addition to the transverse end members 3, 3 already mentioned, there are provided other transverse members or cross-ties 16 and 17 which are preferably above the level of the longitudinal side elements 8. These members serve not only to strengthen and re-enforce the frame, but they also carry foot plates at 18 and 19 respectively which are adapted to partly support electric motors 20 and 21 which are pivoted on the axles 5, 5.

It will be noted that the longitudinal elements 7, 7 and the cross-ties 16, together with the supporting parts therefor, constitute a central housing structure which projects upward above the main end parts of the frame. This housing structure is adapted to enclose the motors and may be provided with a top cover. It will be noted that this housing structure while closed at one end (the left hand end as shown) is open at the other end. The opening at the last said end adapts the frame for the reception of an auxiliary mechanism which is preferably a cable reel mechanism such as is common on locomotives of this type. This cable reel mechanism constitutes no present part of the invention, but it is one of the features of the invention to provide the necessary space for this mechanism.

At the end of the locomotive, adjacent the cross-tie 16, there is provided a comparatively low floor 22, and the space enclosed between the side sections, the corresponding end section and the cross-tie 16

constitute an operator's station in which the electric controller and other devices within the control of the operator are located. At the opposite end of the locomotive there is 5 provided a comparatively low floor 23 and also a covering wall 24. A chamber is formed between the floor 22 and cover 24 which may be utilized for resistance elements, storage batteries or other locomotive 10 accessories.

Preferably as shown in Figs. 1 and 2, draw heads 25, 25 are cast integrally with the end sections 3, 3. This is not essential, however, and in some cases it may be preferable 15 to provide separate draw-heads 25^a, 25^a bolted in place as shown in Figs. 4 and 5.

Preferably two pairs of integrally cast sand boxes 26, 26 and 27, 27 are provided, these being arranged at the four corners of 20 the upward projecting housing structure, and being so arranged as to deliver sand onto the track rails in advance of the wheels. It will be observed that these sand boxes extend upward to the top of the locomotive 25 and are open at the top to permit easy filling. Preferably also provision is made at 28, 28 for control valves to start and stop the flow of sand.

Trolley sockets are shown at 29, 29, these 30 being cast integral and preferably being located immediately adjacent the operator's station. In addition to the trolley sockets, other locomotive accessories and details may be cast integral. For instance, at 30, 30 35 there are shown lugs adapted to support certain links of the brake mechanism which is not shown.

Preferably the structure of the frame is such that the necessary wiring for the motors 40 and other electrical parts of the locomotive can be carried inside of the frame and thus fully protected. Across the front of the locomotive is an inverted channel section 31 which not only provides increased strength 45 for supporting the cable reel mechanism already referred to, but also provides space in which can be located the wires or conductors extending from this cable reel mechanism. As already stated, the longitudinal elements 50 8 of the side sections are channel-shaped and the wires can also extend through these channel-shaped sections. They can also extend vertically through the upright supporting

elements 9 and 10 and along the interior of the upper horizontal frame element 7. Thus 55 the wiring can be carried to any part of the locomotive with the minimum of exposure.

What we claim is:

1. An integral cast frame for electric mine locomotives, comprising main side and end 60 sections and also two cross ties between the side plates, each provided with a foot plate for partly supporting a motor.

2. An integral cast frame for electric mine locomotives, comprising main end and side 65 sections, each side section having two separated horizontal channel-shaped elements with a horizontally elongated recess between them for a leaf spring and with a recess below the lower one for a bearing box. 70

3. An integral cast frame for electric mine locomotives, comprising main end and side sections, each side section having two separated horizontal elements with a vertical tie between them providing two separate horizontally elongated recesses for leaf springs, and each side section also having a bearing box recess below each spring recess, the said frame also comprising cross ties between the side plates, each provided with a foot plate 80 for partly supporting a motor, two pairs of sand boxes located respectively in front of and behind the wheel positions and arranged to discharge sand onto the track rails, and trolley sockets at opposite sides. 85

4. An integral cast frame for electric mine locomotives, comprising main end and side sections, each side section having two separated horizontal elements with a vertical tie between them providing two separate horizontally elongated recesses for leaf springs, and each side section also having a bearing box recess below each spring recess, the said frame also comprising cross ties between the side plates, each provided with a foot plate for partly supporting a motor, two pairs of sand boxes located respectively in front of and behind the wheel positions and arranged to discharge sand onto the track rails, trolley sockets at opposite sides, and 100 draw heads formed integrally with the end sections. 95
